UNITED STATES PATENT OFFICE.

JAMES H. BUSELL, OF BOSTON, MASSACHUSETTS.

HEEL-TRIMMING MACHINE.

SPECIFICATION forming part of Letters Patent No. 280,717, dated July 3, 1883.

Application filed April 23, 1883. (No model.)

To all whom it may concern:

Be it known that I, JAMES H. BUSELL, of Boston, in the county of Suffolk and State of Massachusetts, have invented certain new and 5 useful Improvements in Heel-Trimming Machines, of which the following, taken in connection with the accompanying drawings, is a specification.

My invention relates to that class of heel-trimming machines in which a revolving cutter having its periphery curved longitudinally to correspond substantially to the desired vertical curve to be given to the heel-edge is used; and it consists in certain novel combinations and arrangements of parts, which will be best understood by reference to the description of the drawings and to the claims to be hereinafter given.

Figure 1 of the drawings is a side elevation 20 of a machine embodying my invention. Fig. 2 is an end elevation of the same, and Fig. 3 is a longitudinal section through the cutter and tread and rand guides or gages.

A is the frame of the head, provided with 25 the flange A', by which it may be secured to a suitable column, bench, or other support, and having mounted in the bearings A² A² the shaft B, upon which are secured the driving-pulley C, the hand-wheel D, and the cutter E, 30 all constructed and arranged in a well-known manner. The cutter E has secured to one end thereof, so as to revolve therewith, the tread-surface gage F, and to its other end the rand-guide G. The gage F is made considerably 35 larger in diameter than the greatest diameter of the cutter E, and has its outer portion beveled, as shown, to permit the trimming of heels, the upright sides of which form greater or less angles to their tread-surfaces. The 40 rand-guide G has its outer corner beveled, so as to reduce its thickness at its outer edge, so that it may enter between the upper and the sole, and thus guide the boot or shoe in its movement as it is rotated, in order to present 45 the sides and rear end of the heel to the action of the cutter.

H is a wheel, made in the form of a frustum of a cone, and mounted upon an inclined axis, partly in front of and partly below the cutter 50 E, to serve as a rest or support for the heel

while it is being presented to the action of the cutter. The axis upon which the wheel H is mounted is set in or formed upon the end of the horizontal arm of the knee-shaped rod or bar I, mounted by its vertical arm in a socket 55 formed in one end of the rod J, which in turn is adjustably secured in the ear K on the frame A by means of the set-screw a, as shown in Figs. 1 and 2. The knee-shaped rod I is secured in the socket of the rod J by the set-screw b, so that it may be adjusted vertically, and also about the axis of its vertical portion, while at the same time the rod J may be adjusted endwise in the ear K, and turned about its axis, by virtue of which combined adjustments the wheel H may be set in any required position relative to the cutter E.

The wheel-rest is an improvement upon a fixed or non-rotating rest, because of the greater ease of manipulating the boot or shoe; but it 70 is absolutely essential to its successful operation that it shall be mounted upon an inclined axis, for the reason that unless it is so mounted the boot or shoe cannot be placed in the proper position at the commencement of the trimming 75 when the breast of the heel has to be placed upon the rest, as in many boots and shoes the spring of the shank is so great, or the angle of the shank is such relative to the tread-surface of the heel, that the wheel-rest, if mounted upon 80 a horizontal axis, would interfere therewith and prevent the boot or shoe heel from being placed in the proper position thereon.

The operation of my invention is as follows: The parts being properly adjusted to the particular job in hand, and power being applied to the pulley C to revolve the shaft B and cutter E at a high rate of speed, the breast of the boot or shoe heel is placed upon the upper edge of the wheel-rest H, with its tread-surface bearing against the gage F, and the boot or shoe is revolved till the whole of the sides and rear portion of the heel-edge has been 90 acted upon by the cutter and trimmed to the desired shape, except that the heel-seat is left 95 somewhat full. The boot or shoe is then placed with its breast upon the wheel-rest, as before, but in such a position that the rand-guide G enters the crease between the "upper" and the upper surface of the sole, or "heel-seat," 100

so called, and the boot or shoe is again revolved to bring all parts of the heel-seat into contact with the cutter, and thus retrim the same without changing the shape of the tread-surface of the heel.

5 What I claim as new, and desire to secure by Letters Patent of the United States, is—

10 1. In combination with a rotary cutter adapted to trim the edges of boot or shoe heels, the wheel-rest H, made in the form of a frustum of a cone, and mounted upon an inclined axis, and arranged and adapted to support the boot or shoe heel upon its edge, substantially as described.

15 2. In a heel-trimming machine, the combination of cutter E, the wheel-rest H, made in the form of the frustum of a cone, and the ad-

justable rods I and J, all constructed, arranged, and adapted to operate substantially as and for the purposes described.

20 3. The combination of the cutter E, the tread-surface gage F, the rand-guide G, and the frusto-conical wheel-rest H, all constructed, arranged, and adapted to operate substantially as and for the purposes described.

25 In testimony whereof I have signed my name to this specification, in the presence of two subscribing witnesses, on this 19th day of April, A. D. 1883.

JAMES H. BUSELL.
